CONTAINER

Benjamin M. Williams, St. Louis, Mo., assignor to
 Gaylord Container Corporation, St. Louis, Mo.,
 a corporation of Maryland

Application August 2, 1937, Serial No. 156,900

2 Claims. (Cl. 229—43)

My invention relates to containers, particularly to containers made of paper, fiberboard or the like and having six or more sides. The invention has as its principal object a container of this type 5 which is quite strong and which is adapted to contain a heavy shiftable lading. Other objects and advantages appear hereinafter.

The invention consists principally in a container having a collar member at the end of the 10 container body, a closure sheet covering the end of the body and having flaps projecting into the spaces between the body panels and the panels of the end closure member, said collar member or said body having flaps folded over against the 15 closure sheet and adhesively secured thereto. The invention further consists in laying out the blanks for the several parts in such a way that a maximum number of the creases constituting 20 divisions between parts extend crosswise of the grain or fiber of the material, thereby increasing the strength of the structure. The invention further consists in the container and in the parts and combinations and arrangements of parts hereinafter described and claimed.

25 In the accompanying drawing,

Fig. 1 is an elevation of a container embodying my invention, the closure member at one end of the container being shown in section,

Fig. 2 is a top plan view,

Fig. 3 is a sectional view on the line 3—3 in 30 Fig. 1,

Fig. 4 is a side view of the telescope or cap portion of one end closure member,

Fig. 5 is a side view of one end closure sheet; 35 and

Fig. 6 is a view similar to Fig. 1 of a modification.

The container body 1 is made of paper, fiberboard or other suitable material, preferably of a 40 laminated or multi-ply paper material. The body is divided into panels 2 by means of creases 3 or scores extending longitudinally of the body. Preferably these dividing creases 3 are in the form of fairly wide channels that are outstanding to produce longitudinal ribs 4 along the 45 meeting edges of the outer faces of adjacent panels 2. The body may be made from a flat blank and the overlapping edges 5 of the material secured together by staples 6 or otherwise.

50 The bottom closure member of Figs. 1 to 5 includes a collar 7 having panels 8 corresponding to the panels 2 of the body and fitting over the lower portion of the body 1. The collar 7 is provided with wide creases 9 along the meeting edges 55 of adjacent panels 8. By reason of the outstand-

ing ribs 4 of the body member engaging the corners of the collar panels 8, a space 10 is left between the panels 2 of the body member and the panels 8 of the collar member.

The bottom of the container is covered by a 5 closure sheet 11 having triangular tabs 12 defined by creases 13 or score lines. These triangular tabs 12 extend into the spaces 10 between the body panels 2 and the collar panels 8. The bottom collar 7 has flaps 14 of segmental shape 10 defined by creases 15 or score lines. These flaps 14 are folded over against the bottom closure sheet 11.

The bottom collar 7 and the body member 1 15 may be secured together in any suitable way, as by staples 16. The segmental flaps 14 of the bottom collar may be secured to the bottom closure sheet 11 as by staples 17, or by stitching. Staples 18 or stitching may likewise extend through the body panels 2, the collar panels 8 20 and the tabs 12 of the closure sheet 11.

The top closure member is the same in construction as the bottom closure member including a collar 20 telescoping over the container body 1 and having segmental flaps 21 and a top closure sheet 22 fitting over the top of the body and having triangular tabs 23 extending into the spaces 10 between the body panels 2 and the top collar panels 24. The top collar 20 may be secured to the body 1 by means of staples 25. After 30 the body of the container or keg has been filled, the container being particularly intended and adapted for nails, bolts, nuts and other heavy shiftable lading, the top closure sheet 22 is positioned with its tabs 23 between the body panels 35 2 and the top collar panels 24, after which the segmental flaps 21 of the collar are folded over against the top closure sheet 22 and adhesively secured thereto, as shown at 26.

The arrangement of the grain or fibers in the 40 material from which the several parts are made is selected so as to obtain the maximum strength, bearing in mind the fact that score or crease lines extending along the grain or fiber lines of paper or the like weaken the material much more 45 than such score lines extending across the flow of the grain or fiber. In the container body, the grain or fiber flow is circumferentially of the body as indicated by the lines 30, so that the longitudinal scoring of the body flange extends crosswise 50 of the grain flow. In the top collar 20 and the bottom collar 7, the important consideration is a strong connection between the segmental flaps and the panels. In the collars the grain flow is 55 longitudinally of the body 1, as indicated by the

- lines 31, that is the grain flow is at right angles to the grain flow of the body member 1. This minimizes the weakening effect of the score lines that define the segmental flaps. In the top and bottom 5 collars, the longitudinal creases 9 between panels need not be so deep as in the case of the body, so that there is no serious weakening of the top and bottom collars by reason of the longitudinal score lines.
- 10 The end closure sheets 11 and 22 may be made of corrugated paperboard instead of the plain multi-ply paper construction of the other parts. In only two of the triangular tabs of the closure sheets 11 and 22 do the score lines extend along 15 fiber lines 32, all other scores extending across fiber lines.

In the modification shown in Fig. 6, the collars 40 are mounted inside the body, the segmental securing flaps 41 being provided on the ends of 20 the body panels 2a. The end closure members 42 are mounted in the ends of the body, with their triangular tabs 43 disposed between the collar panels and the body panels. The segmental flaps 41 are folded over against the end closure members 42 and adhesively secured thereto. The collars 40 may be secured inside the body in any suitable way, as by an adhesive or by staples 44.

The above described container construction obtains the maximum strength from material of 25 the kind described. The parts of the container are easily assembled and the filled container will withstand very severe handling, even though filled with heavy shiftable lading.

Obviously the body may have fewer or more sides than the eight shown in the drawing and numerous changes in the details of construction and proportions of parts may be made without departing from the invention so that I do not 5 wish to be limited to the precise construction shown.

What I claim is:

1. A multi-sided container comprising a body member having a multiplicity of longitudinal 10 creases dividing said body into panels, a collar mounted on the end of said body, said collar having panels corresponding to said body panels, and a polygonal closure sheet having tabs projecting from the sides thereof and inserted between 15 panels of said body member and said collar, said collar having flaps folded over against said closure sheet and substantially covering it.
2. A multi-sided container comprising a body member having a multiplicity of longitudinal 20 creases dividing said body into panels, a collar mounted on the end of said body, said collar having panels corresponding to said body panels, and a polygonal closure sheet having tabs projecting from the sides thereof and inserted between 25 panels of said body member and said collar, said collar having flaps folded over against said closure sheet and adhesively secured thereto said flaps covering substantially all of said closure sheet.

BENJAMIN M. WILLIAMS.
